ELECTRICAL PUSHBUTTON SWITCH UNIT

Harry J. Collins, Jr., Bayside, and Charles C. Davis and Raymond L. Erickson, Brookfield, Wis., assignors to Cutler-Hammer, Inc., Milwaukee, Wis., a corporation of Delaware

Filed Aug. 4, 1964, Ser. No. 81,159

Term of patent 14 years

(Cl. D26—13)

Fig.1

Fig.3

Fig.2

Fig.4

FIGURE 1 is a front perspective view of an electrical pushbutton switch unit showing our new design;

FIGURE 2 is a front perspective view thereof wherein the electrical pushbutton switch unit has been rotated 90° from its FIG. 1 position;

FIG. 3 is a side elevational view thereof in fragmentary cross section; and

FIG. 4 is an end elevational view of the switch unit.

The essential features of our design are shown in full lines.

We claim:

The ornamental design for an electrical pushbutton switch unit, substantially as shown and described.
